UNITED STATES PATENT OFFICE

167,380

CAKE COVER

Alfred B. Stotter, Cleveland Heights, Ohio, assignor to Transparent Specialties Corporation, Cleveland, Ohio, a corporation of Ohio

Application January 26, 1952, Serial No. 18,244

Term of patent 14 years

(Cl. D44—19)

To all whom it may concern:

Be it known that I, Alfred B. Stotter, a citizen of the United States, residing at Cleveland Heights, county of Cuyahoga, and State of Ohio, have invented a new, original, and ornamental Design for Cake Cover, of which the following is a specification, reference being had to the accompanying drawing, forming a part hereof.

Fig. 1 is a top plan view of a cake cover, showing my new design;

Fig. 2 is a side elevational view; and

Fig. 3 is a bottom plan view thereof.

Fig. 4 is a vertical sectional view of the base portion taken on line 4—4 of Fig. 3.

This application is a continuation-in-part of my copending application, Serial No. D. 15,670, for Cake Saver and Holder, now abandoned.

I claim:

The ornamental design for a cake cover, substantially as shown and described.

ALFRED B. STOTTER.
